UNITED STATES PATENT OFFICE.

DAVID P. BARRY, OF NEW YORK, N. Y.

DESIGN FOR A PIN OR BUTTON HEAD.

No. 39,164.

Specification for Design.

Patented March 3, 1908.

Application filed January 4, 1908. Serial No. 409,362. Term of patent 7 years.

To all whom it may concern:

Be it known that I, DAVID P. BARRY, a citizen of the United States, residing at the city of New York, borough of Brooklyn, in the county of Kings and State of New York, have invented a new, original, and ornamental Design for a Pin or Button Head, of which the following is a specification, reference being had to the accompanying drawing, forming part thereof.

The figure is a front elevation of a pin or button head partly in perspective, showing my new design.

I claim:

The ornamental design for a pin or button head, as shown.

DAVID P. BARRY.
